CIRCUIT BREAKER EMPLOYING HIGH AND
LOW INTENSITY GAS BLASTGustav E. Jansson, North Quincy, Mass., assignor
to Allis-Chalmers Manufacturing Company,
Milwaukee, Wis., a corporation of Delaware

Application October 3, 1949, Serial No. 119,372

6 Claims. (Cl. 200—148)

1

This invention relates to circuit interrupting devices and more particularly to arc extinguishing means for use in connection therewith. Specifically this invention is an improvement on the invention disclosed and claimed in George A. Burnham's application, Serial No. 126,572, filed November 10, 1949, and Gustav E. Jansson's application, Serial No. 119,373, filed October 3, 1949.

In the construction and operation of circuit interrupters, it is frequently necessary to provide means for extinguishing quickly the arc which is drawn between separable arcing contacts. This arc is usually blown by blowout means, such as an air blast, into an arc chute which is arranged to quench the arc by lengthening it, cooling it, or otherwise.

The interrupting capacity of a circuit breaker interrupter in a high voltage circuit depends to a great extent on the circuit characteristics relating to the rate of increase of recovery voltage when the current is interrupted. Although the breaker may be successful in interrupting the current momentarily, the recovery voltage across the interrupting gap may rapidly rise to such a value that arcing is reestablished before the breaker has sufficiently increased the dielectric strength of the gap. For interrupting higher currents under such conditions, it would be necessary to increase the pressure and the intensity of the gas blast. If it is impractical to increase the gas pressure, the size of the blast passage or the type of gas passage or passages must be varied to provide for greater gas volume or greater interrupting ability. Such changes, however, usually result in either a more expensive or larger breaker.

In accordance with the invention claimed an arc chute is provided adjacent a pair of arcing contacts for receiving the arc at one end thereof and exhausting the arcing products at the other end thereof. The arc chute comprises a first blast passage for interrupting relatively high currents and a second blast passage for interrupting relatively low currents. An insulating blast divider is arranged between the source of fluid under pressure and the arc chute of the circuit breaker for distributing the blast from the point where it arrives in highly concentrated form to the arcing zones. This blast divider comprises a funnel-shaped portion for receiving the blast of fluid from the source and a pair of passages or nozzles for dividing the blast into a high intensity stream which flows through the first blast passage for interrupting high currents and a low intensity stream which flows

2

through the second blast passage for interrupting lower currents. The nozzle for directing the high intensity stream into the first blast passage is asymmetrical at its intake portion and symmetrical at its outlet portion. The nozzle for directing the low intensity stream into the second blast passage may be asymmetrical throughout its entire length. By inserting a suitable resistor in the circuit by means of the arc in the first blast passage, the voltage recovery rate of the current is decreased, and if the circuit is not interrupted by the high intensity blast, it may be interrupted at a greatly decreased current at a much more favorable recovery rate by the comparatively limited blast of the low intensity stream in the second blast passage. In this manner, the interrupting capacity of the circuit breaker, for a given blast pressure and gas consumption, is greatly increased.

20 It is, therefore, one object of the present invention to provide a new and improved arc interrupting device.

Another object of this invention is to provide a new and improved gas blast circuit interrupter 25 which divides a blast of gas into a high intensity stream and a low intensity stream, the high intensity stream flowing through a passage for interrupting a relatively high current and the low intensity stream flowing through a different 30 passage for interrupting a current of relatively low magnitude.

A further object of the invention is to provide a new and improved arc extinguishing device for interrupting a resistor-shunted arc by means 35 of a stream of gas and a predetermined time thereafter extinguishing a second arc in series with the shunting resistor by means of another stream of gas.

40 Objects and advantages other than those above set forth will be apparent from the following description when read in connection with the accompanying drawing in which:

Fig. 1 is a diagrammatic showing partly in cross section of a fluid blast circuit breaker embodying the present invention;

Fig. 2 is a view in cross section of the embodiment illustrated in Fig. 1 taken along the line II—II;

Fig. 3 is a cross sectional view of the embodiment illustrated in Fig. 1 taken along the line III—III; and

Fig. 4 is a cross sectional view of Fig. 1 taken along the line IV—IV.

The cross blast type air blast circuit breaker 55 shown by way of example in Fig. 1 comprises

relatively movable arcing contacts such as fixed contact structure 7 of the "finger" type and a pivoted blade-like contact 8. The fixed contact structure may comprise a plurality of current carrying contacts and an arcing contact as is well known, and is electrically connected to one line terminal 9 of the breaker. The blade-like movable contact is connected to the other line terminal 10. Although in general, circuit breakers of the type considered in Figs. 1, 2, 3 and 4 are provided with a plurality of similar pole structures, one for each phase of a polyphase electric circuit, only one such pole structure is shown in the drawing and the circuit breaker will be described in detail as if it were of the single pole unit type.

The movable contact 8 is suitably connected to an actuating mechanism (not shown) through a connecting rod 11 for operating the movable contact between closed and open circuit positions.

For the purpose of extinguishing the arc formed between the contacts when a power circuit connected thereto is opened, an insulating arc extinguishing structure 12 is arranged with respect to the contacts so that the arc is drawn at the entrance of the structure directly opposite a gas blast supply conduit 13. The conduit 13 is suitably connected through a blast valve (not shown) to a source of compressed gas, such as air, comprising for example a storage tank and compressor equipment (not shown).

The arc extinguishing structure may, for example, define a double barrel arc chute 14 comprising a first blast passage 15 for interrupting relatively high currents and a second blast passage 16 arranged parallel with and spaced apart from passage 15 for interrupting relatively low currents. The blast passages 15 and 16 as illustrated in Fig. 3 have substantially uniform cross sections which may be rectangular or circular in form.

An insulating blast divider 19 is arranged between the gas supply conduit 13 and the arc chute 14 for distributing the blast from the point where it arrives in highly concentrated form by the narrow blast supply conduit 13 to an arc chamber provided for enclosing the arc upon inception thereof. The arc chamber comprises arcing zones 20 and 21 which are spaced apart and situated at the upstream end of the double barrel arc chute 14. The blast divider comprises a funnel-shaped portion 22 mounted immediately adjacent the supply conduit 13 and a pair of nozzles 23 and 24 which diverge from the diverging end of portion 22 toward chute passages 15 and 16.

The sides of the funnel-shaped portion 22 diverge at such a rate that the air expansion within the funnel is limited to the required minimum. The common axis 25 of supply conduit 13 and of funnel-shaped portion 22 of blast divider 19 is situated only slightly to the right of axis 26 of the first blast passage 15 of arc chute 14. Thus, the air blast reaching the downstream end of funnel-shaped portion 22 may pass into nozzle 23 with little restriction.

Nozzle 23 comprises an inlet portion 27 and an outlet portion 28. The inlet portion 27 may be asymmetrical and the outlet portion 28 symmetrical. Nozzle 23 may have a zone of minimum cross sectional area between the upstream and the downstream ends thereof and the walls 29 may converge more rapidly on the upstream end thereof than they diverge on the downstream

end thereof, thus providing a well defined point of maximum flow velocity where the rate of deionization of the arc path is high and the rate of fluid expansion downstream from the point of maximum flow velocity is controlled. Outlet portion 29 of nozzle 23 forms with the wall of the first blast passage 15 a circular air pocket or gap 30.

Nozzle 24 comprises an inlet portion 31 and an outlet portion 32. As indicated in Fig. 3, the inlet and outlet portions 31 and 32, respectively, provide an oblong cross sectional area. The width of nozzle 24 is constant throughout its length and is greater than the width of nozzle 23 at its narrowest point. Nozzle 24 provides a zone of minimum cross sectional area between the inlet and outlet ends thereof.

As illustrated in Figs. 1 and 4 the fixed contact structure 7 projects almost to the longitudinal axis of nozzle 23 and is therefore subjected to an intense air blast upon operation of the arc extinguishing structure.

The walls of the funnel-shaped portion 22 of the blast divider 19, as illustrated in Figs. 1, 2 and 4, define a diverging passage 35 therethrough which accommodates the movable sickle-shaped blade contact 8. These walls closely surround contact 8 and control the escape of compressed air and arc products through passage 35 into blast passages 15 and 16. Passage 35 is provided with a plurality of transversal grooves 36 which tend to establish eddies in the small flow of escaping air and arc products through passage 35. These eddies, in turn, tend to minimize the rate of that flow.

A pair of probe electrodes 37 and 38 may be mounted within blast passages 15 and 16, respectively, for aiding arc extinguishment. Electrodes 37 as illustrated in Fig. 2 may comprise a rectangular portion 39 of refractory metal or alloy which is mounted to extend across the full width of the first blast passage 15 at the downstream end of outlet portion 28 of nozzle 23. A current limiting resistor 40 interconnects electrode 37 and the multiple finger contacts of the fixed contact structure 7, thus lowering the value of the arc current at a predetermined time during arc extinguishment. Electrode 38 may comprise a rectangular portion 41 of refractory metal or alloy which is mounted to extend across the full width of the second blast passage 16 at the downstream end of outlet portion 32 of nozzle 24.

The circuit breaker illustrated in the drawing is shown with the cooperating arcing contacts in the closed circuit position. An opening operation is initiated by admission of gas under pressure to supply conduit 13. The further flow of such gas through passage 35 of funnel-shaped portion 22 of blast divider 19 is at first impeded by contact 8, which obstructs the passage 35. Actuation of the connecting rod 11 moves blade contact 8 toward the right to open the electric circuit.

As the blade contact 8 is separated from the fixed contact 7 an arc is drawn across the arcing zone 20 leading to the first blast passage 15 and substantially concurrently therewith a path is opened for a blast of gas of high intensity through the supply conduit 13 and nozzle 23 of blast divider 19 to the first blast passage 15. This blast includes substantially all the gas being supplied through conduit 13, and drives or loops the arc from zone 20 into passage 15. Frequently the arc is interrupted in the first blast passage

by the blast of gas flowing through nozzle 23. As the blade continues to move toward the right, the arc is extended into zone 21 if it is not already extinguished. The second blast passage 16 and nozzle 24 of blast divider 19 are uncovered and part of the arc is driven or looped from zone 21 into blast passage 16 by the blast from nozzle 24.

In accordance with the invention claimed a funnel-shaped portion 22 of blast divider 19 forms a blast duct, the side walls of which diverge at a rate such that the air expansion within the blast duct is limited to a predetermined minimum value. The blast therefore reaches the arcing zone at a high pressure that has a strong tendency to overcome the back pressure produced by the heat generated by the arc. The common axis of conduit 13 and funnel-shaped portion 22 of blast divider 19 is situated slightly to the right of the axis of the first blast passage 15 of arc chute 14. This is conducive to such a distribution of the blast of air that most of it is caused to escape through the first blast passage 15 which is situated immediately adjacent the stationary finger contacts 7 while only a minor portion of the blast is caused to escape through the second blast passage 16 which is situated at a point remote from the stationary finger contacts 7.

This concentration of the blast in the form of a high intensity stream on the stationary arcing contact structure 7 causes an intense deionization of the arc path at the point where a re-ignition is most likely to occur. The concentration of the blast upon arcing zone 20 and the first blast passage 15 causes a rapid rise of the resistance of the portion of the arc situated at the upstream end of the blast passage 15. The arc rises and comes in contact with probe electrode 37. The section of the arc which is shunted by resistor 40 interconnecting the fixed finger contact structure 7 with the probe electrode 37 arranged in the first blast passage 15 will be rapidly extinguished and replaced after the first current zero by current through the resistor 40. From then on in the interrupting cycle, the task is limited to interrupting a resistor limited arc current of lower intensity and this may be achieved either at the upstream end of blast passage 15 or at the upstream ends of the first and second blast passages 15 and 16, respectively.

By providing rectangular shaped probe electrode portions 39 and 41 extending across the full width of blast passages 15 and 16 respectively, the arc when driven into passages 15 and 16 cannot bypass the electrodes 37 and 38 without being engaged by them. Thus, the full arc extinguishing effect of the probe electrode is assured.

The intensity of the blast of gas necessary to interrupt a resistor limited current of low intensity is much lower than that necessary to interrupt a higher arc current. Therefore, a blast of gas of relatively low intensity is provided through blast passage 16 for interrupting lower currents. The lower intensity of such blast results both from the division of the blast into two streams through nozzles 23 and 24 and of the arrangement of nozzle 24 out of axial relation with supply conduit 13, whereby the momentum of the blast forces it to flow principally through nozzle 23. If the arc is not interrupted in blast passage 15 by the high intensity stream provided by nozzle 23 of blast divider 19 the resistor limited current is then interrupted in blast passage 16 by a lower intensity blast of gas provided by nozzle 24.

Gap 30 formed by the outlet portion 28 of

nozzle 23 and the upstream portion of blast passage 15 forms a circular air pocket which is not likely to be contaminated by arc products and thus tends to preclude an electric breakdown between the first and second blast passages 15 and 16, respectively.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In a fluid blast circuit interrupter, the combination comprising: a source of fluid under pressure, separable arcing contacts for establishing an arc, a conduit for conveying a blast of fluid from said source adjacent said contacts for extinguishing the arc drawn upon separation of said contacts, an arc chute mounted adjacent said contacts for receiving the arc at one end thereof and exhausting the arc products at the other end, said arc chute comprising a first blast passage and a second blast passage, and a blast divider mounted between said conduit and said arc chute comprising a first nozzle having a circular cross sectional area between the ends thereof for directing a high intensity stream of fluid under pressure into said first blast passage for interrupting relatively high currents and a second nozzle having an oblong cross sectional area between the ends thereof for directing a lower intensity stream of fluid under pressure into said second blast passage for interrupting relatively low currents.

2. In a fluid blast circuit interrupter, the combination comprising: a source of fluid under pressure, separable arcing contacts for establishing an arc, a conduit for conveying a blast of fluid from said source adjacent said contacts for extinguishing the arc drawn upon separation of said contacts, an arc chute mounted adjacent said contacts for receiving the arc at one end thereof and exhausting the arc products at the other end, said arc chute comprising a first blast passage and a second blast passage, and a blast divider mounted between said conduit and said arc chute comprising a first nozzle having a circular cross sectional area between the ends thereof for directing a high intensity stream of fluid under pressure into said first blast passage for interrupting relatively high currents and a second nozzle having an oblong cross sectional area between the ends thereof for directing a lower intensity stream of fluid under pressure into said second blast passage for interrupting relatively low currents, said cross sectional area of said second nozzle being substantially smaller than said cross sectional area of said first nozzle.

3. In a fluid blast circuit interrupter, the combination comprising: a source of fluid under pressure, separable arcing contacts for establishing an arc, a conduit for conveying a blast of fluid from said source adjacent said contacts for extinguishing the arc drawn upon separation of said contacts, an arc chute mounted adjacent said contacts for receiving the arc at one end thereof and exhausting the arc products at the other end, said arc chute comprising a first blast passage and a second blast passage, and a blast divider mounted between said conduit and said arc chute comprising a first nozzle having a circular cross sectional area between the ends thereof for

directing a high intensity stream of fluid under pressure into said first blast passage for interrupting relatively high currents, and a second nozzle having an oblong cross sectional area between the ends thereof for directing a lower intensity stream of fluid under pressure into said second blast passage for interrupting relatively low currents, said second nozzle having a cross sectional area substantially smaller than said cross sectional area of said first nozzle and providing a zone of minimum cross sectional area between the ends thereof.

4. In a fluid blast circuit interrupter, the combination comprising: a source of fluid under pressure, separable arcing contacts for establishing an arc, a conduit for conveying a blast of fluid from said source adjacent said contacts for extinguishing the arc drawn upon separation of said contacts, an arc chute mounted adjacent said contacts for receiving the arc at one end thereof, said arc chute comprising a first blast passage for interrupting relatively high currents and a second blast passage for interrupting relatively low currents, and a blast divider mounted between said conduit and said arc chute comprising a first nozzle having a fluid intake portion and a fluid outlet portion for directing a high intensity stream of fluid under pressure into said first blast passage for interrupting relatively high currents and a second nozzle for directing a lower intensity stream of fluid under pressure into said second blast passage for interrupting relatively low currents, said first nozzle being asymmetrical at its fluid intake portion and symmetrical at its fluid outlet portion.

5. In a fluid blast circuit interrupter, the combination comprising: a source of fluid under pressure, separable arcing contacts for establishing an arc, a conduit for conveying a blast of fluid from said source adjacent said contacts for extinguishing the arc drawn upon separation of said contacts, an arc chute mounted adjacent said contacts for receiving the arc at one end thereof, said arc chute comprising a first blast passage for interrupting relatively high currents and a second blast passage for interrupting relatively low currents, and a blast divider mounted between said conduit and said arc chute comprising a first nozzle having a fluid intake portion and a

fluid outlet portion for directing a high intensity stream of fluid under pressure into said first blast passage for interrupting relatively high currents and a second nozzle for directing a lower intensity stream of fluid under pressure into said second blast passage for interrupting relatively low currents, said outlet portion of said first nozzle forming with said first blast passage a gap which prevents an electric breakdown between said first and second blast passages.

6. In a fluid blast circuit interrupter, the combination comprising: a source of fluid under pressure, separable arcing contacts for establishing an arc, a conduit for conveying a blast of fluid from said source adjacent said contacts for extinguishing the arc drawn upon separation of said contacts, an arc chute mounted adjacent said contacts for receiving the arc at one end thereof and exhausting the arc products at the other end, said arc chute comprising a first blast passage and a second blast passage, a pair of probe electrodes mounted one within each of said blast passages and each comprising a metallic portion extending across substantially the full width of said blast passages for engaging the arc, a current limiting resistor conductively connecting said probe electrode mounted within said first blast passage to one of said separable arcing contacts, and a blast divider mounted between said conduit and said arc chute comprising a first nozzle of circular cross section for directing a high intensity stream of fluid under pressure into said first blast passage for interrupting relatively high currents and a second nozzle of oblong cross section for directing a lower intensity stream of fluid under pressure into said second blast passage for interrupting relatively low currents.
